DEVICE FOR PRODUCING CALIBRATING PULSES

Corstiaan le Comte, Hilversum, Netherlands, assignor to Hartford National Bank and Trust Company, Hartford, Conn., as trustee

Application November 1, 1951, Serial No. 254,231

Claims priority, application Netherlands November 9, 1950

4 Claims. (Cl. 250—27)

1

This invention relates to a device for producing calibrating pulses, particularly for the purpose of distance marking on image screens of radar devices.

Known devices of this kind comprise a resonant circuit connected in series with a grid-controlled, normally current-carrying electron tube, said resonant circuit (ringing circuit) being excited when a cut-off pulse is fed to the electron tube and then produces a damped oscillation in its natural frequency for the duration of the cut-off pulse.

In order to compensate the decrease in amplitude of the circuit voltage occurring while the ringing circuit generates oscillations it is known to include the resonant circuit in a Hartley oscillator circuit arrangement or else to feed back a sinusoidal voltage from the resonant circuit in a different manner via an amplifier valve to the said resonant circuit.

The object of the invention is to provide a simplified device of the kind described for producing calibrating pulses having a high phase stability.

According to the invention, the ringing circuit alternating voltage controls a flip-flop circuit arrangement, adapted to produce in the output circuit output pulses coincident with zero passages of the ringing circuit voltage and suitable for calibration, a feedback coil coupled to the ringing circuit coil being also connected to the said output circuit for the supply of current pulses coincident with zero passages of the ringing circuit alternating voltage to the ringing circuit.

In order that the invention may be more clearly understood and readily carried into effect, it will now be described more fully with reference to the accompanying drawing, in which

Fig. 1 shows a circuit arrangement of a device according to the invention, and

Figures 2a to 2e show time diagrams to explain the operation of the device shown in Fig. 1.

Referring to Fig. 1, 1 designates a grid-controlled electron tube, the cathode lead of which includes a cathode resistor 3 shunted by a capacitor 2, whilst the anode of the tube is connected via a resonant or ringing circuit 4 comprising a coil 5, a parallel capacitor 6 and a damping resistor 7, to a tapping 8 of an anode voltage source 9.

The tube 1 is normally current-carrying. If the control grid has a cut-off pulse of the kind denoted V₁ in the voltage diagram shown in Fig.

2

2a supplied to it across terminals 10, the tube 1 is rapidly cut off.

Thus the resonant circuit 4 is excited and "rings" in its natural frequency for the duration of the cut-off pulse.

The damped oscillation thus set up at the ringing circuit 4, illustrated at V₂ in Figure 2b (generally the duration of pulse V₁ comprises a considerably larger number of cycles of the ringing circuit frequency than shown) is fed to a flip-flop circuit which comprises two grid-controlled electron tubes 11 and 12 having a common cathode resistor 13. The control-grid of tube 11 is connected to the anode of the normally current-carrying tube 1, whereas the control grid of tube 12 is connected on the one hand via a coupling capacitor 14 to the anode of the first tube 11 and on the other via a grid resistor 15 to the tapping 8 of the anode voltage source 9. The anode of the tube 11 is connected via an anode resistor 17 to the anode voltage source 9.

This flip-flop circuit known per se has a stable and a meta-stable condition. In the stable or rest condition the tube 12 passes anode current and the tube 11 is cut-off. In the meta-stable condition the tube 11 passes anode current and the tube 12 is cut-off.

If we start with the above-described rest condition at the instant t=0, the grid of the tube 11 has fed to it a positive control voltage, the tube 11 draws current and the voltage across the cathode resistor 13 increases, so that the tube 12 is cut off. The anode current thus occurring in the tube 11 brings about a reduction of the potential of the anode of this tube and this reduction in potential is transmitted by the capacitor 14 to the control grid of the tube 12, which, also due to the action of the voltages at the cathode resistor, results in the tube 12 being suddenly cut off and the tube 11 being simultaneously made conductive. The circuit thus flops over from the stable condition to the meta-stable condition.

This condition subsists for a time period which on the one hand is dependent on the periodicity of the sinusoidal voltage V₂ supplied to the control grid of the tube 11 and on the other is dependent on the time constant of the flip-flop circuit. This time constant mainly depends on the values of coupling capacitor 14, grid resistor 15 and anode resistor 17.

In the meta-stable condition of the flip-flop circuit the potential of the control grid of tube 12 increases by the capacitor 17 becoming charged so that the control grid of tube 12 substantially reassumes its original potential within a half

cycle of the sinusoidal voltage V_2 that is to say approximately at the instant, at which V_2 assumes a very steep slope and passes the zero axis in a negative direction. At this instant or thereabouts the cutting off of the tube 12 is removed and the circuit flips back from the metastable condition into the stable condition. At the subsequent zero passages of the alternating voltage V_2 or thereabouts the cycle described is repeated. The variation of the voltage at the anode of the tube 11 and that of the voltage at the control grid of tube 12 are shown in Figures 2c and 2d respectively.

During the time the tube 12 is cut off a rectangular current pulse is set up at its anode and is fed to a differentiating network included in the anode circuit of the tube 12 and constituted by a coil 16 and a resistor 17 connected in parallel therewith. Periodically at the commencement and at the end of such a current pulse short pulses of positive and negative polarity respectively of the kind shown in Fig. 2e are set up across the differentiating network 16-17, said pulses being coincident with zero passages of the ringing circuit voltage V_2 . These short voltage pulses are obtained across output terminals 18 and may be fed, if desired after amplification and removal of the negative pulses, as calibrating pulses for example to the deflecting system of a cathode ray tube in radar devices.

The short pulses set up across the output circuit of the tube 12 and being coincident with the zero passages of the ringing circuit voltage V_2 are fed to a feedback coil 9 connected in series with the differentiating network 16-17 and give rise to feedback current pulses in the circuit 4 which are coincident with zero passages of the ringing circuit alternating voltage.

By the supply of a positive current pulse to the circuit at each zero passage in a positive direction of the circuit voltage and the supply of a negative current pulse at each zero passage in the negative direction of the voltage V_2 , the decrease in amplitude of the ringing circuit voltage during the time the resonant circuit 4 rings is compensated each half cycle. Since the feedback current pulses only occur at the zero passages of the ringing circuit voltage V_2 or thereabouts the phase of the circuit alternating voltage is substantially not affected so that a particularly high phase stability of the calibrating pulses produced is obtained.

The anode circuit of the tube 1 includes a resistor 20 connected in series with the resonant circuit 4, said resistor constituting, together with the conductive tube 1, a potentiometer for the obtainment of such a bias voltage at the control grid of the tube 11 that when the tube 1 passes current the tube 11 remains cut off. The presence of the resistor 20 also governs the "starting point" of the flip-flop circuit, since when the tube 1 is cut-off the voltage across the resistor 20 (the voltage drop across the circuit 4 is comparatively low) is suddenly removed. The tube 11 of the flip-flop circuit then becomes rapidly conductive at the moment of time $t=0$.

In the circuit described the apices of the calibrating pulses, as may be seen from the time diagrams shown in Fig. 2, are not completely coincident with the zero passages of the sinusoidal voltage V_2 , but occur sooner by a time τ which is small compared with a cycle T of the circuit voltage. The time τ can be corrected by connecting a supplementary grid bias voltage source 21 in series with the grid leak 15.

What I claim is:

1. Apparatus for generating calibrating pulses comprising an electron discharge tube having a control grid, a resonant circuit, means connecting said resonant circuit in series with said tube to a source of potential to produce a current flow in said tube, means to apply pulses to said grid to cut-off current flow in said tube whereby damped oscillations are developed across said resonant circuit, a flip-flop device coupled to said resonant circuit and responsive to said damped oscillations to produce pulses coincident with zero passages of said damped oscillations, and means coupled to said flip-flop device to feed back said pulses to said resonant circuit to maintain phase stability of the pulses yielded by said flip-flop device.
2. Apparatus for generating calibrating pulses comprising an electron discharge tube having a control grid, a resonant circuit, a source of direct potential, means connecting said tube in series with said resonant circuit across said source normally to produce current flow in said tube, means coupled to said grid to apply pulses to said tube to interrupt current flow therein whereby said circuit is shock excited to produce damped oscillations, a flip-flop device coupled to said resonant circuit and responsive to said damped oscillations to produce pulses coincident with zero passages of said oscillations, and means including a coil coupling the device to said resonant circuit to feed back pulses to said resonant circuit to maintain phase stability of said pulses yielded by said device.
3. Apparatus for generating calibrating pulses, for purposes of distance marking on a radar screen, comprising an electron discharge switching tube having a cathode, a control grid and an anode, a resistor, a resonant circuit, a direct voltage source having its negative end connected to said cathode and its positive end connected through said resonant circuit in series with said resistor to said anode to produce a current flow in said tube, means to apply pulses to said grid to interrupt current flow in said tube whereby said circuit is shock excited to produce damped oscillations, a flip-flop device coupled to said anode to produce pulses coincident with zero passages of said oscillations, and means including a coil coupling said device to said resonant circuit to feed back pulses thereto to maintain phase stability of said pulses produced by said device.
4. Apparatus, as set forth in claim 3, wherein said flip-flop device is constituted by two electron discharge tubes each having a cathode, a grid and an anode, a common cathode resistor for said tube, a resistance, means applying a positive bias through said resistance to the grid of one tube normally to maintain current flow therein, a capacitor coupling the grid of said one tube to the anode of the other tube, and means connecting the grid of said other tube to the anode of said switching tube.

CORSTIAAN LE COMTE.
